Inventor

Louis Rommeiks

United States Patent Office.

LOUIS ROMMEIKS, OF NEWARK, NEW JERSEY.

Design No. 3,739, dated November 2, 1869.

DESIGN FOR ORNAMENTING BRIDLE-BITS.

The Schedule referred to in these Letters Patent and making part of the same.

To all whom it may concern:

Be it known that I, LOUIS ROMMEIKS, of Newark, county of Essex, and State of New Jersey, have originated and designed a new Ornament for Bridle-Bits, of which the following is a specification.

My design is an ornament on the guards, consisting of circular strings of balls with star-points radiating from the centre, and terminating in fleur-de-lis, which gives to the bridle-bit and harness a unique and beautiful appearance, as shown in the drawings, representing a face-view of the bit-guards with the ornament thereon.

D D are the guards.

K K represent the circular strings of balls;

L, the star-points; and
M, the fleur-de-lis.

Having described my invention,
What I claim, and desire to secure by Letters Patent, is—

The design for ornamenting a bridle-bit, as herein set forth.

In testimony whereof, I have hereunto set my signature, this 9th day of September, A. D. 1869.

LOUIS ROMMEIKS.

Witnesses:

A. NEILL,
WILLIAM McAULIFFE.
